UNITED STATES PATENT OFFICE.

CHARLES K. GREEN, OF GADSDEN, ALABAMA.

WATER-COOLER.

1,372,135.

Specification of Letters Patent. Patented Mar. 22, 1921.

Application filed August 25, 1919. Serial No. 319,618.

To all whom it may concern:

Be it known that I, CHARLES K. GREEN, a citizen of the United States, residing at Gadsden, in the county of Etowah and State 5 of Alabama, have invented certain new and useful Improvements in Water-Coolers, of which the following is a specification.

The object of this invention is to provide a sanitary water cooler in which a maximum 10 supply of cold drinking water will be furnished with a given quantity of ice. The invention seeks to provide a water cooler for public or private buildings which will provide a constant supply of cold water without attention other than replenishing the 15 ice, and which may be readily cleaned and freed from the sediment deposited by melting ice. The invention also seeks to provide a device for the stated purpose in which 20 the drinking water will not come in actual contact with the ice but will be exposed to the cooling influence of the ice from below the same and all around it.

The invention is illustrated in the accompanying drawings, in which—

Figure 1 is a vertical section of a water cooler embodying my improvements;

Fig. 2 is a horizontal section on the line 2—2 of Fig. 1, and
30 Figs. 3, 4, 5 and 6 are similar views taken respectively on the lines 3—3, 4—4, 5—5 and 6—6 of Fig. 1.

In carrying out the invention, I employ a main container 1 which may be of any 35 preferred dimensions and form and is intended to be located at any desired point within a building. This container will be fixed in place and from its lower end an outlet pipe 2 will extend to the outside of the 40 building or to any other place of discharge, being ordinarily connected with a sewer. The upper end of the container is normally closed by a cover 3 which will fit closely thereon so that the ice placed within the 45 container will be effectually shut off from contact with the air. In the bottom of the container 1, I place a supplemental container 4 which will be of a shape corresponding to the shape of the main container 50 1 and will be supported upon the bottom of the same by spacing blocks 5 which may be of any convenient material and will be disposed at such intervals as may be deemed desirable. These blocks will support the inner 55 container or tank out of contact with the bottom of the main container so that the

waste water from the melting ice may circulate below the supplemental container and pass to the outlet pipe 2. The supplemental container will be of slightly less diameter 60 than the main container 1 so that a space will be provided between the two containers to permit the circulation of the cooled air and of the water from the melting ice. The supplemental container 4 is closed throughout the extent of all its walls except at diametrically opposite points in its top wall 6 where it will be provided with openings 7 to respectively receive the lower ends of a nipple or coupling 8 and an outlet pipe 9. 70 Within the said inner tank or supplemental container, I provide a series of baffles or partitions 10 which extend in opposite directions from the perimeter of the tank and terminate in spaced relation to the said perimeter or vertical wall of the tank. As shown most clearly in Fig. 5, these partitions or baffles are disposed with their free ends arranged alternately at opposite sides of the center of the tank or the diameter 75 passing between the openings 7, the result being that the water within this tank will be forced to circulate through the same in a tortuous path and its escape will, consequently, be retarded and it will be held 80 within the tank and exposed to the cooling influence of the ice for a maximum period. The nipple 8 forms a connection between the tank 4 and the lower end of an upper tank 11 which is disposed within the main container 1 and arranged closely to but spaced from the vertical wall of the main container, as shown clearly in Fig. 1. The nipple 8 85 furnishes the only communication between the upper and the lower tank and also aids 90 in supporting the upper tank, additional supports being provided by spacing blocks 12 which are disposed at intervals between the top of the lower tank and the bottom of the upper tank, as shown and as will be 95 readily understood. The upper tank terminates below the top of the main container and the outlet pipe 9 extends up through the inner ice chamber provided by the upper tank and then extends over the top of the 100 upper tank and out from the side of the main container, as shown at 13. The outwardly extending branch of the pipe 9 may be equipped with any preferred means for permitting use of the water immediately adjacent the container or may be carried to any 105 desired point where the cool drinking water

may be most conveniently used. In the upper end of the upper tank at a point preferably diametrically opposite the outlet pipe 9, I provide an inlet nipple 14 which is 5 connected by an elbow 15, containing a cut-off valve, with the pipe 16 leading from the water main or other point of supply. Midway the height of the upper tank, I provide a horizontal partition 17 therein which has 10 an opening 18 at a point diametrically opposite the inlet nipple 14, as shown clearly in the drawings.

It is thought the operation of my water cooler will be readily understood. The ice, 15 indicated at 19, is placed within the chamber provided by the lower tank 4 and the inner vertical wall of the upper tank 11 through the top of the main container 1 as will be readily understood on reference to Fig. 1. 20 The flow of water into the cooler may be regulated by the valve in the elbow 15 so that, even with the outlet wide open, there will be no excessive flow and waste of the cold water. The water flowing through the 25 nipple 14 cannot pass directly to the bottom of the upper tank but will be forced to flow around the same over the partition 17 to the opening 18 through which it will pass to the lower portion of the upper tank. It will 30 then be forced to flow around the lower portion of the upper tank to the nipple 8 through which it will escape into the lower tank and by reason of the interposition of the alternating baffles 10 within the lower 35 tank it will be caused to flow in a tortuous path before escaping into the outlet pipe 9 through which it will rise. It will be readily noted that the water at no time comes into direct contact with the ice nor is it exposed to the hands of any user or to anyone 40 who may be placing ice within the cooler or cleaning the cooler after the ice has been consumed. The ice is in direct contact with the walls of the tanks, however, and the 45 water from the melting ice will surround the lower tank so that the cooling influence of the ice will be exerted upon the water from the time it enters the cooler until it is drawn therefrom. It is to be especially 50 noted that the tanks are comparatively shallow or narrow so that the entire body of the water will be subjected to the cooling influence of the ice and the chilled walls of the tanks, and the outlet pipe 9 passes upwardly through the body of ice so that all 55 the heat of the water will be extracted. The device is exceedingly simple in construction and arrangement and will be found very durable inasmuch as there are no moving 60 parts and consequently there is nothing to become disarranged or inoperative. The ice may be very easily placed within the cooler

and when it is necessary to clean the cooler of sediment deposited by the melted or melting ice this result can be easily accomplished 65 by merely flushing the main container so that the sediment will be washed into the escape pipe 2 and thence pass to the sewer. The cooler will, of course, be made in various sizes to meet all demands and various 70 changes may be made in the details of construction and arrangement without departing from the invention as the same is defined in the appended claims. The outlet 13 may be disposed close to the inlet 16 and the flow-controlling cut-off valve arranged in the 75 inlet pipe outside the tank. If the outlet be equipped with a constantly open bubbler, the tanks 4 and 11 will be relieved of all pressure. 80

Having thus described the invention, what is claimed as new is:

1. A cooler for liquids comprising a main container, a tank supported on the bottom of the container and spaced from said bottom, an outlet leading from the bottom of the container, an upper annular tank supported by the lower tank and spaced therefrom and in communication therewith, said upper tank defining a chamber to receive a 90 cooling medium means for supplying liquid to be cooled to the upper tank through the top of the same, means for withdrawing the liquid from the lower tank through the chamber defined by the upper tank, and 95 means for effecting a tortuous circulation of the liquid through the two tanks.

2. A cooler for liquids comprising a main container having an outlet in its bottom, a tank supported upon the bottom of the container in spaced relation thereto and spaced from the vertical wall of the container, a plurality of baffles within the said tank, said baffles being disposed with free ends of the alternate baffles at opposite sides of the 100 tank, an outlet pipe rising from the top of the tank at one side of the same, an inlet nipple at the opposite side of the tank, an upper annular tank connected to and communicating with the lower tank by the 105 said nipple and supported upon the lower tank in spaced relation thereto, said upper tank defining an inner chamber adapted to receive a cooling medium and through which the outlet pipe from the lower tank passes, 110 means for supplying liquid to be cooled to the upper tank at the top of the same, and a partition intermediate the top and bottom of the upper tank and having an opening therethrough out of alignment with the nipple and with the means for supplying liquid 115 to the tank.

In testimony whereof I affix my signature.
CHARLES K. GREEN. [L. S.]
